UNITED STATES PATENT OFFICE

2,285,112

ADJUSTABLE CHAIR

John M. Dorton, Bonner Springs, Kans.

Application July 13, 1939, Serial No. 284,264

1 Claim. (Cl. 155—116)

My invention relates to an adjustable chair and one object of the invention is the provision of a chair of this character in which the seat may be adjusted forward or backward and the back may be adjusted upward or downward through pressure exerted by the occupant of the chair.

A further object of the invention is the provision of means for securing the seat and the back of the chair in any of their adjusted positions.

Another object is to connect the seat and the back of the chair in such manner that as the back is let down to a reclining position the seat is moved forward to keep the chair balanced so that it will not tip backward under the weight of the occupant.

Other objects will hereinafter appear, and in order that the invention may be fully understood reference will now be had to the accompanying drawings, in which—

Fig. 1 is a side elevation of the chair with the upholstery and some of the other parts removed, and the head-rest adjusted to its lowermost position in full lines and adjusted to its uppermost or idle position in dotted lines.

Fig. 2 is a plan view of the chair with the head-rest and some of the other parts removed.

Fig. 3 is a longitudinal sectional view of the chair on line 3—3 of Fig. 2, with the head-rest added and adjusted to its uppermost position in full lines and to an intermediate position in dotted lines.

Fig. 4 is an enlarged section on line 4—4 of Fig. 1 of one of a pair of hinges which connect the back to the seat frame of the chair.

Fig. 5 is an enlarged cross section on line 5 of Fig. 1 showing one of a pair of guideways and one of a pair of rollers for adjusting the chair back to different inclinations when the chair seat is moved forward or backward.

In carrying out my invention I provide a pair of supporting members 2 each of which is preferably formed from one piece of tubing and comprises front and rear legs 4 and 6, respectively, and an arm rest 8 uniting said legs. The arm rests 8 are upholstered with soft rubber or other suitable material 9 and the legs are mounted upon casters 10 which are preferably swiveled upon the lower ends of the legs so that they may readily turn in different directions. The supporting members 2 are united at their front and rear portions with transverse members 12 and each supporting member is provided with a rail

14 fixed to the associated front and rear legs 4 and 6, respectively.

A seat frame 16 located between the supporting members 2 is mounted for forward and backward movements upon the rails 14. Each side of the seat frame 16 comprises a lower member 18 bent upward at its rear end and connected to an upper member 20 which is curved downward at its forward end and fixed to the forward end of the member 18. The lower seat members 18 are united at their front and rear ends with transverse members 22 and provided near their rear ends with rollers 24 adapted to traverse the respective rails 14, which latter are equipped near their forward ends with rollers 26 upon which the respective seat members 18 are adapted to travel so that the seat frame 16 may be moved forward or backward with but little effort on the part of the occupant of the chair. The lower seat members 18 have spaced rods 18a connected thereto to support the lower portion of a cushioned frame hereinafter described.

The seat frame 16 is held in any of its adjusted positions with either one of a pair of racks 28 and a detent 30. Racks 28 are fixed upon the respective lower seat members 18 where they may be engaged by the detent 30 which is fixed to a hand lever 32 secured to a shaft 34 mounted in bearings 36 fixed to the under sides of the respective rails 14. The hand lever 32 is applicable to either end of the shaft 34 for the convenience of right or left handed users, so in order that it may be readily removed from one end of shaft 34 and applied to the other end thereof the lower end of the hand lever is split and equipped with a bolt 38 which may be tightened to firmly secure the hand lever upon the shaft. The detent 30 is yieldably engaged with the associated rack 28 by a coil spring 37 connected at one end to one of the rails 14 and connected at its other end to a collar 39 fixed to shaft 34.

The back frame 40 of the chair is preferably made of tubular stock and comprises two sides united at their upper and lower ends with transverse members 42 and each side comprises front and rear members 44 and 46, respectively, the former of which is bent rearwardly at its upper end and fixed to the upper end of the latter 50 which is bent forward at its lower end and fixed to the lower portion of the front member 44. The rear members 46 have transverse rods 46a connected thereto to coact with the rods 18a in supporting the cushioned frame above referred to.

The front members 44 of the back frame 40 are connected at their lower ends to the rear ends of the upper members 20 of the seat frame 16 with respective hinges 48 so that the back frame 40 may be raised or lowered to different positions. Each hinge 48 comprises a pair of members 52 and 50 fixed to the adjacent ends of the seat frame members 20 and the back frame members 44, respectively, and operably connected with a transverse pin or screw 53. Each hinge member 52 is recessed to receive a felt washer 56 which may be saturated with a suitable lubricant to facilitate the operation of the respective hinges and eliminate squeaks or other noises.

Inclination of the back frame 40 to various positions is automatically controlled on forward or backward movement of the seat frame 16 with a pair of rollers 58 and a pair of guideways 60. The rollers 58 are mounted at the upper reduced portions of a pair of upwardly extending supporting elements 62 consisting preferably of sheet metal and rigidly secured at their enlarged lower ends with suitable means such as screws 64 to the respective rails 14. Each guideway 60 extends downward at an angle from the associated front member 44 to the rear member 46 of the back frame 40 and is fixed at its ends to said members 44 and 46.

A cushioned frame which may be upholstered is removably associated with the seat and back frames 16 and 40, respectively. The cushioned frame includes a plurality of coil springs 66, back and seat units 69 and 70, respectively, to each of which a number of the coil springs 66 are secured, a plurality of wire strands 68 secured at 35

their upper ends to the upper portion of the unit 69 and at their lower ends to the coil springs 66 on the forward part of the unit 70, and clips 67 which secure the wire strands 68 to the upper ends of the seat springs 66 and the forward ends of the back springs 66. Members 69a and 71 on the back and seat frames 40 and 16, hold the units 69 and 70, respectively, removably in place.

The upper portions of the two side strands 68 10 are provided with bearings 72, in which one end of respective arms 75 are operably mounted, the opposite end of each arm being operably connected to a head-rest 78 adapted to be adjusted to the respective full and dotted line positions disclosed by Figs. 1 and 3.

Having thus described my invention, what I claim and desire to secure by Letters Patent is:

In a chair of the character described, a pair of rails, a seat-frame movable forward and backward upon said rails, a back-frame including two sides hinged at their lower ends to said seat-frame, each side being formed of tubular stock and comprising front and rear members the former of which is bent backward at its upper 25 end and fixed to the upper end of the rear member which latter is bent forward at its lower end and fixed to the lower portion of the front member, a straight guideway for each side of the back-frame extending downward from the front 30 member to the rear member, a roller extending into each guideway, and a pair of supporting elements extending upwardly from the rails and on the upper portions of which the rollers are mounted.

JOHN M. DORTON.
